UNITED STATES PATENT OFFICE.

ALVAH BLACKBURN, OF ALUM BANK, PENNSYLVANIA.

COW-TAIL HOLDER.

1,383,902.

Specification of Letters Patent. Patented July 5, 1921.

Application filed February 14, 1921. Serial No. 444,910.

To all whom it may concern:

Be it known that I, ALVAH BLACKBURN, a citizen of the United States, residing at Alum Bank, in the county of Bedford and State of Pennsylvania, have invented certain new and useful Improvements in Cow-Tail Holders; and I do declare the following to be a full, clear, and exact description of the invention, such as will enable others skilled in the art to which it appertains to make and use the same.

This invention relates to that class of devices known as cow tail holders, the object of the same being to provide a simple and effective device of this class which will effectively hold the tail.

Another object of the invention is to provide a device of this class which is made therefrom a single length of wire bent to form a pair of spaced operating handles, a centrally and horizontally disposed spring coil, a pair of spaced tail and leg engaging jaws, and a pair of fingers for engaging the hairs on the tail to prevent the latter from being pulled upwardly through the jaws, the wire being so bent and twisted upon itself as to reinforce the handles and jaws.

Other objects and advantages of the invention will be apparent during the course of the following description.

In the accompanying drawings forming a part of this specification and in which like numerals are employed to designate like parts throughout the same:

Figure 1 is an elevational view of a tail holder constructed in accordance with this invention showing the same in use.

Fig. 2 is an enlarged top plan view of the holder.

Fig. 3 is a still further enlarged perspective view of the same with portions of the operating handles removed.

Referring to the drawings wherein the preferred embodiment of the invention is clearly shown, the numeral 1 designates a central horizontally disposed spring coil, 2 indicates a pair of rearwardly extending spaced operating handles, 3 indicates a pair of spaced forwardly extending tail and leg engaging jaws, and 4 denotes a pair of fingers which serve a purpose to be hereinafter set forth. While the parts may be formed in various other ways, I prefer to construct them from a single length of wire. To this end, the wire is first bent between its ends to form the coil 1, after which, the wire has

its opposite ends extended rearwardly in spaced relationship bent upon itself at 5, extended toward and beyond the central spring coil, bent upon itself again at 6, extended rearwardly toward the coil, bent upon itself at 7 and the free end extended through said coil to form the aforesaid fingers 4. In bending the wire, the outer free ends of the jaws 3 are flared outwardly from each other to facilitate engagement of these jaws with the hind-leg of the cow. Furthermore, after the wire is bent in this way the parts thereof forming the operating handles and jaws are twisted upon themselves as shown to reinforce these parts. Thus, it will be seen that a simple and effective device is formed which can be manufactured and retailed at an extremely small cost.

In using the device, the operating handles 2 are moved toward each other so as to separate the jaws 3. The jaws are then engaged with the adjacent leg of the cow just above the knee as disclosed in Fig. 3. Now, by releasing the grip on the operating handles, the coil spring 1 serves to cause the jaws to tightly grip the animal's leg. The animal's tail is of course, placed between the jaws 3 prior to engaging the latter with her legs. When the device is in position as shown, switching of the tail is absolutely prevented. Furthermore, in case the tail is drawn upwardly through the jaws 3, the fingers 4 will become entangled in the hairs on the free end of the tail and thus prevent it from becoming freed.

While I have shown and described my improved holder or clasp as being especially designed for holding the tail of a cow to prevent annoyance to the attendant or milker, I wish it to be understood that the device may well serve some other purposes. However, as before stated, the device is especially designed for use as a cow tail holder and it will be found extremely advantageous and useful when used for such purposes. It not only overcomes the annoyance to the milker by preventing switching of the tail, but it prevents dirt and other impurities from being swept into the pail during the milking operation which often times happens when no means is provided for holding the tail. The construction of the device is such that it will be effectively held in position on the leg at all times but, at the same time, it will not effect too tight a grip to injure the tendon on which it is engaged. Furthermore,

by forming the device from a single length of wire, it is rendered extremely inexpensive to both the manufacturer and the user and it is so simple in construction that it can be 5 easily used. These and other features and advantages of the invention have, no doubt, become apparent from the foregoing description and drawing.

Advantageous and effective results are 10 practically insured with the construction and arrangement shown and described. However, minor changes may be made within the scope of the adjoining claims.

I claim:

15 1. A cow tail holder made from a single length of wire bent to form a central and horizontally disposed flat spring coil, a pair of spaced rearwardly extending handles, and a pair of spaced forwardly extending 20 jaws, the outer ends of the latter being flared to facilitate engagement of the jaws with the cow's leg, and the free ends of the wire being bent and passed forwardly through

said coil and providing comparatively short fingers for catching into the hair on the tail. 25

2. A cow tail holder formed from a single length of wire bent between its ends to provide a central horizontally disposed spring coil, the wire being directed rearwardly from the coil, bent upon itself, directed forwardly and extended beyond the coil, again bent upon itself, extended rearwardly to the coil and the free ends bent upon themselves and passed forwardly through the latter, forming spaced handles, 30 spaced jaws, and hair-engaging fingers, all of which are disposed in a plane with the coil, the wire forming the handles and jaws being twisted upon itself to reinforce these parts, and the outer free ends of the jaws being flared to facilitate engagement with the 35 cow's leg.

In testimony whereof I have hereunto set my hand.

ALVAH BLACKBURN.
